(57) **CLAIM**

The ornamental design for a combined pry bar and holder, as shown and described.

DESCRIPTION

FIG. 1 is the perspective view of a combined pry bar and holder;

FIG. 2 is the front view of the combined pry bar and holder;

FIG. 3 is the back view of the combined pry bar and holder;

FIG. 4 is the left side view of the combined pry bar and holder;

FIG. 5 is the right side view of the combined pry bar and holder;

FIG. 6 is the top view of the combined pry bar and holder; and,

FIG. 7 is the bottom view of the combined pry bar and holder.

The broken lines in the drawings represent stitching lines of the combined pry bar and holder.
